INVENTOR
Herbert M. Sturgis
ATTORNEY

UNITED STATES PATENT OFFICE.

HERBERT M. STURGIS, OF KANSAS CITY, MISSOURI, ASSIGNOR TO SAVE-A-HANDLE PRODUCTS CO., OF KANSAS CITY, MISSOURI, A CORPORATION OF MISSOURI.

MOP HEAD AND FASTENER THEREFOR.

1,420,639.

Specification of Letters Patent. Patented June 27, 1922.

Application filed December 8, 1920. Serial No. 429,245.

To all whom it may concern:

Be it known that I, HERBERT M. STURGIS, a citizen of the United States, residing at Kansas City, in the county of Jackson and State of Missouri, have invented certain new and useful Improvements in Mop Heads and Fasteners Therefor; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to mop heads and fasteners therefor, one of the objects being to provide an efficient method of attaching mops to handles whereby the mop head and handle may be conveniently secured together and disassociated whenever the occasion demands.

In the drawings,—

Fig. 1 is an elevational view of a mop provided with a head connection constructed in accordance with my invention.

Fig. 2 is a perspective view of the mop head and the coupling detached.

Fig. 3 is a longitudinal, sectional view through the coupling member and mop head.

Fig. 4 is a detail perspective view of the coupling collar, and

Fig. 5 is a detail perspective view of a slightly modified form of mop head adapted to be engaged by the type of coupling shown in Figs. 1 to 4.

In carrying out the invention I provide a handle 1, which may be of usual construction and secured to one end thereof is a sleeve or ferrule 2, extending slightly beyond the end of the handle and enclosing the longitudinal grooves 3 and 4, which are adapted to receive the elongated pins or studs 5 and 6 of the mop head fastener. The prongs 5 and 6 are continuations of the staple or fabric holder loop 7, which bind the fabric to the head portion 8, shown as comprising a concavo-convex member, the peripheral, outwardly flared flange 9 of which embraces the mop fabric 10.

The mop head, consisting of the disk 8 and its flange 9, is provided with oppositely disposed lugs or projections 11 and 12, struck out from the metal of which the

head consists, preferably by a die operation. 55 The lugs 11 and 12 are adapted to be engaged by a coupling sleeve 13, mounted upon the ferrule 2 and having inwardly projecting cam flanges 14 and 15, the respective ends of the flanges being spaced apart, as 60 at 16, the spaces 16 being substantially equal to the widths of the projections 11 and 12, which are adapted to be received in the notches 17 and 18 of the ferrule 2, the end of the ferrule being provided with semi-circular flanges 19 and 20, as seen in Fig. 2.

The prongs 5 and 6 are connected to the loop portion 7 by offset portions 21 and 22, which constitute locks to prevent longitudinal play of the disk in one direction, the 70 play of the disk in the opposite direction being opposed by the filled-in portion 23 of the mop fabric 10.

When the parts are properly assembled and it is desired to attach the mop head to the handle, the two prongs 5 and 6 will be introduced into the grooves or recesses 3 and 4 with the lugs 11 and 12 in the spaces 17 and 18. Then the coupling ring 13 will be moved longitudinally of the ferrule 2 80 until the lugs have passed through the spaces 16, whereupon the ring 13, which is preferably milled, will be turned so that the cam flanges 14 and 15 bind on the lugs and draw the head into the socket 24, formed by the 85 protruding ends of the ferrule 2 until the flanged portion 9 rests upon the flanges 19 and 20, whereupon the head will be locked to the handle.

If it is desired to release the head from 90 the handle for any purpose, the coupling ring can be turned until the spaces 16 register with the lugs 11 and 12, whereupon the head may be detached.

In Fig. 5 I have shown a slightly modified form of mop head, particularly applicable for use in connection with the so-called cedar mops. In this form a triangular frame 25 is shown, which may be of the usual construction. The frame carries a 100 plate 26 having upstanding ears 27 and 28 with a pivoted member 29 secured thereto, the member having lugs 30 and 31 corresponding to the lugs 11 and 12 on the disk 8. The lugs 30 and 31 may be engaged in 105 the same manner as the head disk 8 to secure the modified form to the handle. In this case, however, there will be no engaging

prongs or projections corresponding to those designated 5 and 6 in the preferred form.

What I claim and desire to secure by Letters-Patent is:

- 5 1. In combination, a mop fabric supporting head having diametrically opposite lateral projections, a handle having a fixed ferrule thereon, the end of which projects beyond the handle to form a socket, the edge of the ferrule having a peripheral flange intersected by projection receiving notches cut in the walls of the ferrule, and a cam ring on the ferrule for engagement with the under faces of the projections to locate them in the recesses.
- 10 2. In combination, a mop fabric supporting head comprising a concavo-convex plug, an adjustable loop member carried by the head to support a mop fabric, a handle having a socket to receive the plug, the walls of the socket having vertical cut-out portions, lugs on the plug projecting through the cut-out portions, and a cam ring on the handle having means for engaging the outer faces of the projections to retain the plug within the socket.
- 15 3. In combination, a mop fabric supporting head comprising a concavo-convex disk having oppositely disposed projections, longitudinally extending pins carried by the head, a handle having pin-receiving recesses, a socket member to receive the head, and a cam ring movable on the handle for engaging the projections.
- 20 4. In combination, a mop head comprising a concavo-convex disk, a mop fabric-engaging staple projecting through said disk and having offset portions to prevent longitudinal movement of the staple, a handle having recesses to receive the free ends
- 25
- 30
- 35
- 40

of the staple, and means for locking the head to the handle.

5. In combination, a mop head comprising a concavo-convex disk, a mop fabric-engaging staple projecting through said disk and having offset portions to prevent longitudinal movement of the staple, a handle having recesses to receive the free ends of the staple, means on the handle to prevent rotative movement of the head, and means for locking the handle and head together.

6. In combination, a mop head comprising a disk having oppositely projecting lugs, means for securing a mop fabric to the disk, a handle, a ferrule on the handle having oppositely located recesses to receive the lugs or projections on the disk, and a cam ring on the handle having cam flanges to ride over the lugs to draw the head into intimate contact with the handle.

7. The combination with a mop head comprising a disk having a staple projecting therethrough, the loop of which serves as a mop fabric binder, the ends of the staple projecting through the disk, lugs on the disk, a handle having longitudinal recesses to receive the projecting ends of the staple, a ferrule surrounding the recesses and extending beyond the handle member to form a socket to receive the head, opposite portions of the ferrule being notched to receive the lugs or projections on the head so that the head cannot turn with respect to the handle, and a ring on the ferrule engaging the lugs or projections on the head to draw it into the socket.

In testimony whereof I affix my signature.

HERBERT M. STURGIS.
